UNITED STATES PATENT OFFICE.

ALFRED B. FITZGERALD, OF BLACKSTONE, VIRGINIA.

AUTOMATIC AIR-CO尤PLING DEVICE.

1,181,755.

Specification of Letters Patent.

Patented May 2, 1916.

Application filed June 4, 1914. Serial No. 842,917.

To all whom it may concern:

Be it known that I, ALFRED B. FITZGERALD, a citizen of the United States, residing at Blackstone, in the county of Nottaway 5 and State of Virginia, have invented certain new and useful Improvements in Automatic Air-Coupling Devices, of which the following is a specification.

My invention relates to new and useful 10 improvements in devices for coupling the air lines of a train and resides in the provision of a simple, reliable and highly effective device that will automatically couple the air lines of cars so as to form continuous 15 air lines, in an expeditious manner.

An object of importance is to provide a 20 device of the character described that will automatically open valves in the ends of the air lines of each car when the cars are coupled and close the valves when the cars are uncoupled.

Another object of importance is to provide a coupling device of the character described that is yieldingly held in extended 25 operative position and is permitted lateral movement to prevent uncoupling of the device when the train is rounding a curve.

Another object is to provide a novel arrangement of guide arms that are carried 30 by the coupling means and coöperate when the device is coupled to insure the proper connection of the air lines.

My invention further aims to improve 35 coupling devices so as to render them more practical, reliable and efficient in operation, inexpensive to manufacture and commercially desirable.

The above and additional objects are accomplished by such means as are illustrated 40 in the accompanying drawings, described in the following specification and then more particularly pointed out as claimed.

With reference to the drawings, wherein I have illustrated the preferred embodiment 45 of my invention as it is reduced to practice, and throughout the several views of which similar reference numerals designate corresponding parts: Figure 1 is a top plan view of my improved coupling device showing the same in coupled position and the supports for securing the coupling devices to the cars in section, Fig. 2 is a horizontal sectional view of one of the coupling members constructed in accordance with my 50 invention, Fig. 3 is a front elevation of one of the coupling members, Fig. 4 is a detail

perspective view of a slightly modified form of coupling member to be employed in connection with a plurality of air lines instead of a single line, Fig. 5 is a fragmentary detail perspective view of the supporting bar for the coupling members, and Fig. 6 is a cross sectional view taken on the line 6-6 of Fig. 1 and looking in the direction of the arrow, and showing the rear end piece of 65 the frame and the manner of connecting the rear end of the supporting bar thereto. Fig. 7 is a cross sectional view taken on the line 7-7 of Fig. 1, and looking in the direction of the arrow, and showing the front end 70 piece, and the manner of connecting the squared end of the supporting bar thereto.

Referring to the drawings by characters of reference the numerals 1 and 2 designate as entireties coupling members, each of the 75 coupling members comprises an approximately rectangular head 3 carrying on one side forwardly extending arms 4 and 5 that are arranged in spaced relation to each other, one above the other. The arm 5 is 80 arranged uppermost and adjacent its outer end is bent forwardly and upwardly as at 6. The arm 4 is lowermost and adjacent its outer end is bent downwardly and outwardly as at 7. On the other side of the 85 body portion 3 is carried an arm 8 that extends forwardly from the head 3 and is curved outwardly as at 9 at its outer end. The arms 8 on the coupling members 1 and 2 are designed to fit between the arms 4 90 and 5.

Connected with the rear faces of the coupling members 1 and 2 are supporting bars 10 that are tubular and extend through frames 11 carried by the cars beneath the 95 usual car couplings. The bars 10 are approximately rectangular as at 12 for distances equivalent to approximately half their length and the rectangular portions 12 are disposed so as to slide through longitudinal slots 13 formed in the end pieces 14 of the frames 11 and have their free ends received by sockets 11'-11' carried by the rear faces of the coupling members. The frames 11 comprise side bars 15 and integrally connected front and end pieces, designated respectively, by the numerals 14 and 16. The bars 10 are slidable through suitable openings 10a formed in the rear end pieces 16 of the frames 11. A plurality of 105 supporting bars 17 are secured as at 18 at their lower ends to the side bars 15 of the 110

- frame 11 and are suitably connected at their upper ends to the cars after a manner not shown. Helical expansion springs 19 are mounted upon the bars 10 and at their ends engage stop pins 20 carried by the bars 10 and the inner faces of the end pieces 16 of the frames 11. The innermost ends of the bars 10 are suitably connected with the train line pipes, not shown.
- 10 Formed in each of the heads 3 of the coupling members is a U-shaped horizontal air passage 21 that communicates with the atmosphere at the forward face of each head 3. A tubular projection 22 tapered toward its outer end and preferably formed integral with the head 3 communicates with one end of the U-shaped air passage 21. A frusto conical enlarged opening 23 is formed at the other end of each U-shaped passage.
- 15 The tubular projections 22 fit snugly within the frusto conical openings 23, when the coupling members are in coupled position so as to form a continuous air line. A horizontal passage 24 is formed in each of the coupling heads 3 and at its rear or inner end communicates with the tubular bar 10. The passage 24 also communicates with the central part of the passage 21. Slidably mounted within the passage 24 is a cylindrical
- 20 valve member 25 that is provided with a transverse opening 26 intermediate its ends. An integral valve stem 27 extends through a small partition wall 28 that separates the passage 24 from an opening 29. The stem 27 extends into the opening 29 and at its outer end is provided with an enlarged head 30 that projects outwardly for a distance equivalent to approximately two-thirds of its length. The projecting heads 30 are arranged to engage each other when the device is coupled so that the openings 26 in the valves 25 which are normally out of registration with the passage 21 are moved against the tension of expansion springs 31
- 25 arranged within the openings 29, to register with the passages 21. It will thus be seen that when the coupling members move into coupling engagement with each other, the valve is open and a continuous air line 32 formed. The projections 22 fit within the enlarged frusto conical openings 23 and a comparatively tight joint is provided. The springs 19 serve to hold the coupling members in extended position and in tight engagement with each other as the springs 19 are slightly compressed when the coupling members are in coupled position as illustrated in Fig. 1 in the drawings. The arms 4, 5 and 8 serve to guide the coupling members when they are moved toward each other and insure the positioning of the extensions 22 within the enlarged frusto conical openings 23. The springs 31 tend to automatically close the valves 25 when the coupling members are uncoupled.

With reference to Fig. 4 wherein I have illustrated a modified form of my invention, the coupling head 3 is formed larger than in the preferred form and provided with a plurality of the tubular projections 22, 70 valves 25, frusto conical openings 23, passages 21 and tubular supporting bars 10. The series of projections and openings being arranged one above the other as shown in Fig. 4 in the drawings. The modified 75 form is particularly designed for use on trains wherein a number of air lines are employed and as illustrated in the modified form three air lines may be controlled.

With reference to the foregoing description and accompanying drawings it will be readily seen that I have provided simple and reliable coupling means that is entirely automatic in operation, dispensing with the necessity of some member of the train's crew manually coupling the train line and thus saving time and obviating possibility of loss of life through accidents.

In practice, I have found that the form of my invention, illustrated in the drawings and referred to in the above description, as the preferred embodiment, is the most efficient and practical; yet realizing that the conditions concurrent with the adoption of my device will necessarily vary, I desire to 95 emphasize the fact that various minor changes in details of construction, proportion and arrangement of parts may be resorted to, when required, without sacrificing any of the advantages of my invention, 100 as set forth.

What is claimed is:—

1. An automatic air coupling device comprising co-acting coupling members, each of the coupling members comprising an enlarged head and a tubular supporting arm having one end connected to the head at a medial point, the said head having a U-shaped passage therein, the opposite ends of the sides of the U-shaped passage opening 110 into the forward end of the head, and its arcuate portion communicating with the tubular support, and a straight passage extending through and having one end opening into the head and located between and 115 parallel with the sides of the U-shaped passage, and having its opposite end communicating with the arcuate portion of the U-shaped passage and the tubular support, a valve mounted within the straight passage 120 and slidable across the arcuate portion of the U-shaped passage and into the tubular support, and adapted to control communication between the sides of the U-shaped passage and the tubular supporting arm. 125

2. In an automatic air coupling device, co-acting coupling members each having an air passage therethrough, tubular supporting bars for the coupling members, and communicating with the air passages, means for 130

controlling the communication between the tubular members and the air passages, frame members each including diverging side bars and connecting end bars, one of the said end bars being arcuate in configuration and each of the said end bars having a horizontal slot therein, adapted to receive one of the tubular supporting bars, springs positioned within the frame members and em-

bracing the tubular supporting bars, and engaging the arcuate end bars as and for the purpose specified. 10

In testimony whereof I affix my signature in presence of two witnesses.

ALFRED B. FITZGERALD.
